INVENTOR

William A. Pentecost
By Chas. St. Burleigh
Attorney

UNITED STATES PATENT OFFICE.

WILLIAM A. PENTECOST, OF WORCESTER, MASSACHUSETTS.

STEAM-GENERATOR.

SPECIFICATION forming part of Letters Patent No. 315,160, dated April 7, 1885.

Application filed June 30, 1884. (No model.)

To all whom it may concern:

Be it known that I, WILLIAM A. PENTECOST, a citizen of the United States, residing at Worcester, in the county of Worcester and State of Massachusetts, have invented certain new and useful Improvements in Steam-Generators; and I declare the following to be a description of my said invention sufficiently full, clear, and exact to enable others skilled in the art to which it appertains to make and use the same, reference being had to the accompanying drawings, which form a part of this specification.

My present invention relates to improvements in apparatus for heating buildings and apartments by steam, the object thereof being to provide a compact, efficient, and economical steam-heating apparatus that can be supplied at comparatively small cost, and which can be set up and safely operated in the basement of ordinary dwelling-houses without requiring unusual care and attention more than that required for the ordinary heating-furnaces.

The particular features of invention claimed are hereinafter definitely specified.

In the drawings, Figure 1 is a vertical sectional view of my improved heating apparatus. Fig. 2 is a horizontal sectional view through the upper part of the fire-chamber and its surrounding walls and spaces. Fig. 3 is a vertical section of the weighted steam check-valve.

In referring to parts, A denotes the boiler, which is made with upper and lower sections, bolted together as indicated. The lower section forms the sides of the fire-chamber B, and is composed of an outer and inner shell connected at the bottom, and embracing a narrow annular water leg or space, a, between them, while a series of radially-arranged tubes or flues, b, passing through from side to side near the upper part, serve to connect the shells and permit the passage of smoke or products of combustion. Upon the top of the lower section or casting, riveted or bolted to the inner rim, is a copper plate, A', which forms the bottom of the boiler or crown-sheet of the fire-chamber, and upon the outer rim is secured the dome or top section, A'', of the boiler. The bottom plate, A', is supported by a brace-plate, a', and stay-bolt, a'', in connection with a bar,

a'', fixed across the dome, as shown, which gives a firm but elastic support to the center of the thin bottom plate, A''. Arranged about the lower boiler-section is a petticoat-sheet, C, 55 reaching from the central joint downward past the flues b and inclosing an annular space, c', in which the heated gases are carried downward along the exterior surface of the water-leg before passing upward in the annular space 60 c' within the outer casing, G, which covers the dome of the boiler A and supports the flue or pipe G', which may lead to the chimney, as convenient.

D indicates a tank or reservoir containing 65 a float, F, that works the lever e and valve E, for regulating the inflow of water to the generating-chamber of the boiler. The arrangement of the tank D, float F, lever e, and valve E, the manner of combining them with the 70 generating-chamber, and their mode of operation for maintaining the water-level, are substantially similar to devices described in Letters Patent No. 298,024, granted to me May 6, 1884, said devices serving to give only a thin 75 sheet of water over the fire-plate A' of the generator.

In the top of the regulator-chamber D, above the float F, I arrange a reciprocating rod, f, provided at its top end with a hand-knob, 80 whereby the rod can be pressed down onto the float or end of the lever e, for the purpose of forcing down said lever and opening the valve E when desired for letting more water into the boiler or testing the action of the valve 85 from the exterior of the apparatus. A small chamber, E', is arranged below the valve E, in which the end of said valve is guided, and from which the sediment can be drawn off by means of the thumb-cock e', so that the valve 90 will not become clogged. A glazed tube, D', projecting to the exterior of the casing, serves to reveal the condition and water-level in the boiler.

The fire-chamber B is adapted for burning 95 coal, and is in size about the same as that of an ordinary house-furnace, or, say, from sixteen to twenty-four inches diameter, (more or less,) according to the size of apparatus. In the upper part of the chamber I arrange a deflector or guard, I, which projects inward and upward from the furnace-walls in front of the

tubes *b*, in the manner indicated. This deflector may be provided with a tubular channel, *i*, perforated with a series of small holes, and adapted for admitting air or oxygen to mingle with and consume the gases. The ends of the air-passages may open through the front of the casing or through the furnace-door *B*², and movable dampers or valves *i'* may be fitted thereto in any convenient manner for regulating the inflow of air.

If preferred, the deflector could be made without the air-passages *i*. The deflector *I* is preferably made in two parts or castings and supported on lugs or projections on the inner rim of the boiler-section, and so that the castings can be readily removed and replaced through the doorway when desired to give access for clearing out the tubes *b*. The deflector *I* serves to direct the flames and hot gases against the bottom plate, *A'*, to prevent the throwing of coal into the tubes when firing, and also to admit air for thoroughly burning the gases from the fuel as they pass along the bottom plate and through the tubes *B*.

The boiler and casing rest upon a base, *H*, in which is located the ash-pit *h*. Said pit is provided with a close-fitting upwardly-swinging door, *H'*, that is connected with the steam-pressure-diaphragm regulator *K*, for governing the draft of air into the fire and regulating the heat thereof in the usual manner.

R indicates the grate, supported in the base *H* by suitable trunnions on its rim *R'*, and by a shaft, *T*, having a disengageable connection at *t* to facilitate dumping the grate. A bar, *S*, may also be provided for shaking the grate without dumping it.

The construction and arrangement of the grate devices may be of any suitable kind other than that shown, if preferred.

J indicates the steam-pipe leading to the radiators for heating the several apartments, and *J'* denotes the return-pipe, through which the water from the condensation of the steam in the radiators flows back into the tank *M*, from which tank the generator is supplied with water through the pipe *m*, under control of the valve *E*.

The tank *M* is made as a close vessel of proper size, and is located at a convenient height—say four to six feet, more or less—above the generator-boiler, or near the ceiling of the basement or room in which the apparatus is used. The tank may be provided with a gage to show the water-level, and with a discharge-pipe and cock, *n*, for drawing off sediment that settles from the water. The pipe *m* extends a short distance up into the interior of the tank, and it is also provided with a trap, *M'*, or mud-drum, to catch any particles of solid matter that would be liable to interfere with the perfect working of the valve *E*.

From the steam-pipe *J*, or communicating with the boiler *A*, I arrange a pipe, *L*, leading into the upper part of the tank or reservoir *M*, to equalize the pressure above and be-

low the water, and thus counteract any tendency to force the water backward through the feed-valve *E*.

The pipe *L* may be provided with a check-valve, *P*, having a weight or spring of sufficient force to balance a pressure slightly less than that of a column of water corresponding in height to the water-level of the tank above the valve *E*, if desired, to cut off the steam-pressure from the tank, except when the steam-pressure rises above the normal amount.

By the employment of devices such as above described, and their arrangement for action in the manner set forth, I produce a very desirable heating apparatus that can be practically, safely, and economically used for heating ordinary dwelling-houses, and which can be readily operated in situations where it would be impractical, if not impossible, to employ the ordinary kinds of steam-heaters, as well as in any desired or more convenient situation.

The size and capacity of the apparatus may be varied according to requirements and purpose; but it will be observed that for a given generating or heating capacity the size or bulk of the apparatus is comparatively very small, and also that it can be successfully operated with a small amount of coal.

I am aware that a steam-boiler has heretofore been patented in which openings through the water-leg or portion surrounding the furnace are employed, in connection with dampers or shutters, for closing the same during the normal operation of the boiler, said openings being for the purpose of giving direct draft when starting the fire. I do not, therefore, herein include a construction of such nature as within the scope of my claims.

What I claim as of my invention, and desire to secure by Letters Patent, is—

1. The boiler or generator, as herein described, composed of the lower section, having outer and inner shells surrounding the fire-chamber *B*, with annular water-space *a*, the series of radial tubes *b*, the bottom plate, *A'*, secured to the inner shell, and the dome *A*, secured to the outer shell of said lower section, with the internal braces for supporting the center of said plate *A'*, substantially as shown.

2. The combination, with the boiler *A*, having the lower section or water-leg, *a*, surrounding the fire-chamber, and the series of radial tubes *b*, of the petticoat-sheet *C*, attached at the central joint and extending downward past said tubes, substantially as shown, and for the purpose set forth.

3. The combination, with the boiler having the lower annular section surrounding the fire-chamber, and provided with a series of radial tubes or openings, *b*, of a deflector or bridge-plate, as *I*, extending inwardly and upwardly in front of said tubes, substantially as and for the purpose set forth.

4. The combination, with the boiler having the fire-chamber *B* in its lower section, and provided with a series of radial tubes, *b*, and entrance-door *B*², of a deflector, as *I*, detach-

ably supported within said fire-chamber in front of the tubes *b*, and formed in sections which can be conveniently removed and replaced through said doorway, as set forth.

5. The combination, with the boiler having fire-chamber *B* and tubes *b*, as shown, of a deflector or rim, *I*, extending upward within said chamber in front of said tubes, and provided with air-passage *i* and perforations for admitting air to the fire-chamber, and shutters *i'*, for regulating the inflow of air to said passages, substantially as set forth.

6. The combination, with a generator constructed substantially as described, and having an internal regulating apparatus, of the 15 sliding rod *f*, supported in the shell of the generator, as and for the purpose set forth.

Witness my hand this 26th day of June, A. D. 1884.

WILLIAM A. PENTECOST.
